[57] CLAIM

The ornamental design for a shower fixture having twin outlets extending from a single inlet, as shown.

DESCRIPTION

FIG. 1 is a perspective view of a shower fixture having two outlets extending from a single inlet showing our new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and

FIG. 7 is a bottom plan view thereof.

FIG. 1

FIG. 4

FIG. 5

FIG. 6

FIG. 7
